(57) **CLAIM**

The ornamental design for a side frame for modular furniture as shown and described.

DESCRIPTION

FIG. 1 is a front view of a side frame for modular furniture; FIG. 2 is a rear view of FIG. 1;

FIG. 3 is a top view of FIG. 1, the bottom view being a mirror image thereof;

FIG. 4 is a right view of FIG. 1, the left view being a mirror image thereof;

FIG. 5 is a front, left perspective view of FIG. 1;

FIG. 6 is a front, right perspective view of FIG. 1;

FIG. 7 is a rear, left perspective view of FIG. 1;

FIG. 8 is a rear, right perspective view of FIG. 1;

FIG. 9 is another rear, left perspective view of FIG. 1; and, FIG. 10 is a perspective view of FIG. 1 shown in an environment of use.

The broken lines showing a bench seat and additional side frame for modular furniture in FIG. 10 is for the purpose of illustrating environmental structure and forms no part of the claimed design.

1 Claim, 10 Drawing Sheets
